UNITED STATES PATENT OFFICE

2,248,090

SELF-CONTROLLED CARBURETOR

Milton J. Kittler, Detroit, Mich., assignor to
George M. Holley and Earl Holley

Application October 30, 1939, Serial No. 301,942

5 Claims. (Cl. 123—119)

The object of this invention is to automatically control the mixture ratio of an airplane engine by means of an exhaust gas analyzer.

In the drawing:

Figure 1 shows the general layout of the invention.

Figure 2 shows in greater detail the automatic mixture indicator and controller.

Figure 3 shows the desired mixture ratio characteristics at various percentages of maximum power.

In the figures, 10 is the exhaust gas analyzer connected in the usual manner to the exhaust pipe 11. The carburetor 12 is located in the air inlet 13 immediately above the mixture outlet 14. The mixture is supplied to a supercharger 15 and is delivered through the inlet passages, one of which No. 16 is shown. A pipe 17 connects this air inlet passage 16 with the mixture indicator and controller, the casing for which is numbered 23. The mixture admitted through the passage 16 is admitted to the cylinder 18 which cylinder is connected to the crankshaft 19 driving the propeller 20, which is provided with the usual constant speed propeller mechanism 21. The exhaust connection from the cylinder 18 is shown at 22.

The electricity for operating the exhaust gas analyzer is obtained from a cell 24 connected through a wire 25 with the exhaust gas analyzer 10. The current flows from the exhaust gas analyzer through the conductor 26 to the mixture indicator and controller contained in the casing 23, from which it flows through either of the two wires 27 and 28 which lead into the relay or amplifier 29. The current for the amplifier is obtained from a battery 30 and the amplified current leaves through either of the conductors 31 or 32. Depending on which wire 27 or 28 is used, the current enters the motor 33 through either of the wires 31 or 32 which determines the direction of rotation of the motor and, through the movement of the lever arm 34 which is connected through the link 35 with the mixture control lever 36 and the carburetor 12, the mixture strength. The control lever 36 corresponds to the mixture control lever as marked Z in patent to Chandler 2,125,886. These mixture ratio control devices usually operate by applying back suction, or suction existing between the throttle and the supercharger, to the carburetor float chamber where a float is used. In the case of floatless carburetors they are used as shown in the above mentioned patent. The carburetor throttle is operated by a link 48.

The details of the mixture indicator and controller 23 are indicated in Figure 2.

In Figure 2, 23 indicates the casing and the three wires 26, 27 and 28 correspond to the three wires 26, 27 and 28 of Figure 1. The pointer 37 is moved by the exhaust gas analyzer and indicates on the scale 38 the mixture ratio. This mixture ratio in Europe is measured as 14 to 1, or 12 to 1, but in the United States, the mixture ratio is referred to as .07, .08, etc. This figure refers to the fraction of a pound of fuel per pound of air and is reciprocal of the figure used in Europe. The pointer 37 moves to correspond to the exhaust gas analyzer in the method described in American patent to Hebler 1,860,541. The pipe 50 corresponds to the inlet passage 1 of the Hebler patent and the outlet pipe 49 corresponds to the outlet 8 of the Hebler patent.

When the needle 37 moves to the left, current is conducted to the conductor 28 and an amplified current is supplied to the motor 33 through the conductor 32, and the motor 33 turns the lever 34, link 35, and lever 36 in the direction 25 making the mixture richer. When the needle 37 moves to the right, the reverse happens and the mixture is made leaner.

The result is that the location of the rod 39 carrying the two contacts 40, 41, which respectively engage with the pointer 37, determines the mixture ratio within very close limits. This rod 39 is moved by the lever 42 which is pivotally mounted in the box 23 and is connected to the rod 43 which is moved by the aneroid barometer 44 contained in a housing 45. This housing 45 is subjected, through the pipe 17, to the pressure or vacuum existing in the pipe 16 leading to the inlet valve of the cylinder 18, depending on the position of the throttle valve.

Figure 3 shows the desired mixture ratio control. At 30% of the rated power, or 3000 pounds of air in a 1400 horsepower engine taking 10,000 pounds of air per hour, the mixture ratio stands at .071. This mixture ratio is maintained up to an air flow of 7000 pounds of air per hour, or 1000 horsepower or 70% of maximum power. At that point, the mixture ratio is increased rapidly until it reaches .11 at 100% power, which is the take-off power, the power necessary to leave the ground with the slightest possible delay. When climbing at less than 75% of maximum power, the mixture is leaner than is desired. To overcome this, a movable stop 46 operated by a lever 47, is provided. In the position shown, the stop 55 corresponds to the mixture ratio .071. When the

lever 47 moves over to the right, the stop 46 rises and the mixture ratio then cannot be leaner than .085. The lever 42 is forcibly moved to the position shown in broken lines in Figure 2, and the lever 47 is held in position by a ratchet.

Operation

When the engine is operating with the lever 47 in the position shown in Figure 2, the depression in the air entrance 16 to the cylinder 18 is such that the pressure in the pipe 17 acting on the aneroid barometer 44 causes the rod 43 to move to the right against the stop 46. Therefore, when cruising lean the mixture ratio is kept constant at .071. When the lever 47 is moved to the right, the stop 46 is moved to the left, and the two contacts 48 and 49 are dragged over to the right, so that the mixture ratio is now held constant at .085. There is sufficient gear reduction in the motor 33 so that the mixture ratio does not hunt when the contact 49 is engaged by the pointer 37. In other words, when the mixture is richer than desired, the arm 36 moves slowly to make the mixture lean, and when the mixture is lean and the contact 48 engages with the pointer 37, the mixture gradually becomes richer. The mixture ratio therefore, fluctuates slowly between the limits .070 and .072, and averages .071.

Of course, with different engines different ratios give maximum economy and mixture ratios of .069 are frequently used. It will be noticed that at extreme altitudes the mixture ratio will be .071 at all positions of the throttle.

What I claim is:

1. The combination with an internal combustion engine having air inlet passages and a fluid fuel supply, of means responsive to the chemical composition of the exhaust gas and to the density of the air at the inlet passage for automatically regulating the ratio between the rate at which the fuel is fed to the engine and the rate at which air is supplied to the engine for the combustion of the gasoline.

2. The combination with an internal combustion engine having air inlet passages and a fluid fuel supply, of means responsive to the chemical composition of the exhaust gases and of the

density of the air at the inlet passage for automatically decreasing the ratio between the rate at which the fuel is fed to the engine and the rate at which air is supplied for its combustion on a decrease in the density of the air whereby the cruising lean mixture is leaner than the take-off mixture.

3. In combination, an internal combustion engine having a supercharger, an exhaust pipe and a carburetor equipped with a throttle and a mixture control valve, a gas analyzer adapted to be operatively connected to the exhaust pipe of the engine, and including an indicating element, an electrically controlled relay responsive to movements of the indicating element, a power unit operated by the electricity derived from the relay and connected to the mixture control valve, means responsive to the absolute air-fuel-mixture pressure at the air-fuel-mixture entrance to the engine for moving the mixture ratio indicating element and thus controlling the mixture ratio at the figure-determined by the said density.

4. In combination with an internal combustion engine an exhaust pipe and a carburetor equipped with a throttle valve and a mixture control valve, an electrically operated motor connected thereto, a gas analyzer adapted for operative connection with the exhaust pipe of the engine and including a movable element, the movement of which responds to changes in the mixture ratio, two electrical contacts adapted to be engaged alternatively by said movable element and thus adapted to conduct electricity to said electrically operated motor to alternatively move said mixture control valve in the direction to make the mixture rich and to make the mixture lean, means responsive to the density of the air-fuel-mixture at the point where it enters the engine for moving the two electrical contacts so that at maximum density the mixture ratio is at its maximum richness.

5. In a device as set forth in claim 4 in which there is a movable stop adapted to limit the movement of the two electrical contacts so as to establish a minimum mixture ratio below which the mixture cannot fall so long as the fuel supply is maintained.

MILTON J. KITTLER.
